UNITED STATES PATENT OFFICE.

EMIL OLSON, OF ROCHESTER, NEW YORK, ASSIGNOR TO OLSON MANUFACTURING CORPORATION, OF ROCHESTER, NEW YORK, A CORPORATION OF NEW YORK.

SASH-HOLDER.

1,393,309.

Specification of Letters Patent. Patented Oct. 11, 1921.

Application filed November 24, 1920. Serial No. 426,286.

To all whom it may concern:

Be it known that I, EMIL OLSON, a citizen of the United States, and resident of Rochester, in the county of Monroe and State of New York, have invented certain new and useful Improvements in Sash-Holders, of which the following is a specification.

The present invention relates to sash holders and more particularly to the type shown in an application filed by me on the 22nd day of May, 1920, Serial No. 383,572 in which there is employed a supporting member attached to the meeting rail of the upper sash and having mounted thereon for vertical and rocking movement, a wedge member for coöperation with the stile of the upper sash, an object of this invention being to provide in connection with the wedging member, a device which will normally lie out of engagement with the stile, but which will enter into biting engagement therewith upon the rocking of the wedging member on the forcing of either one of the sashes while the sash holder is effective for holding said parts against movement, thereby preventing any further movement of either of the sashes in the direction of opening.

To these and other ends the invention consists of certain parts and combinations of parts, all of which will be hereinafter described, the novel features being pointed out in the appended claims.

In the drawings:

Fig. 1 shows the sash holder in side elevation mounted in operative position, the upper and lower sash being shown in fragmentary section;

Fig. 2 is a plan view of a sash holder; and

Fig. 3 is a vertical section.

Referring more particularly to the drawings, 1 indicates the meeting rail of the lower sash and 2 the meeting rail of the upper sash. The supporting member of the sash holder embodies in this instance, a pair of spaced ears 3 connected at their lower ends by a base plate 4 which is adjustably mounted on an attaching plate or member 5, the latter being secured by a single screw 6 to the meeting rail 1 of the lower sash. Adjustment of the supporting member on the attaching member may be secured through a thumb screw 7 journaled at 8 in an extension 9 on the base 4 of the supporting member, said screw engaging in a

threaded opening formed in a lug 10 projected upwardly from the attaching plate 5. The wedging member, in this instance, is formed from a single piece of sheet metal with a front face 11 which is depressed to provide a pocket in which the face engaging piece 12 is received, this piece, in this instance, being in the form of a rubber disk. Extending from opposite sides of the front plate 11 are two flanges 13 which have their free edges 14 beveled and coöperating with a pair of rollers 15, the latter being arranged on the outer sides of the ears 3 on a shaft 16 which extends through said ears and projects from opposite sides of the support.

The wedging member is preferably supported on a supporting member by a lever 17 which has depending lugs or flanges 18 provided with slots 19 through which the pivot pin 16 extends. This lever is through a pivot pin 20, pivotally connected with the flanges 13 of the wedging member. A spring 21 surrounds the pin or shaft 16 between the ears 18 and has one arm coöperating with the base 4 of the support and the other arm coöperating with the lever 17 so as normally to move the lever in a direction to shift the wedging member downwardly on the support. Depression of the lever shifts the wedging member in an upward direction on the rollers 15. The thumb screw 7 is adjustable to maintain proper coöperation between the surface 12 and the stile of the upper sash and the attaching plate or member 5 turns on the screw 6 so that the plane of the surface 12 may lie parallel with the face of the sash which is engaged by such surface. No claim is made, in this application, to any of the foregoing parts *per se*.

The feature of this invention is the provision of the wedging member with a device which will bite into the stile of the upper sash in the event that an attempt is made to force either of the sashes in the direction of opening. This device, in this instance, is in the form of a tooth or prong 22 projected upwardly from one of the flanges 13 and thence forwardly toward the upper sash, the end of the prong lying slightly in rear of the engaging surface of the pad 12.

With this arrangement, under the ordinary operation of the wedging member 13, the penetrating projection 21 will not en-

gage the upper sash with force enough to penetrate such sash, but in the event that either of the sashes are forced after such sashes have been secured by the wedging member, then there is a tendency for the wedging member to rock and swing the penetrating projection 21 into biting engagement with the upper sash so that both sashes are securely held against further movement without any danger of the wedging member slipping on the upper sash.

What I claim as my invention and desire to secure by Letters Patent is:

1. A sash holder comprising a supporting frame, a wedging member coöperating with said frame to move vertically thereon and also to rock so as to coöperate properly with a flat face of a sash, and a penetrator having its penetrating point lying slightly in rear of the engaging face of the wedging

holding member and adapted to swing with said member into engagement with the sash to lock the latter against movement in the direction of opening if the sash is forced.

2. A sash holder comprising a supporting frame, a wedging holding member formed with a portion to coöperate with a flat face of the sash and with two flanges coöperating with said frame to permit the wedging holding member to move vertically on said supporting frame and also to rock, and a penetrator formed integrally with one of said flanges and having a penetrating point lying in a plane slightly in rear of the engaging portion of the wedging holding member and adapted to swing into engagement with the sash to lock the latter against accidental movement in the direction of opening if the sash be forced.

EMIL OLSON.
